UNITED STATES PATENT OFFICE.

ELLOF S. RYERSON, OF DAYTON, WASHINGTON.

AIR REGULATOR FOR REFRIGERATORS.

Application filed June 23, 1925. Serial No. 39,665.

This invention relates to air regulators for refrigerators and has as one of its objects to provide an air regulator that is operable under thermostatic control.

Another object of the invention is to provide an air regulator that will automatically permit the escape of the warmer air from refrigerators.

A further object of the invention is to provide an air regulator that will provide for a circulation of air in the warmer air zone of the refrigerator.

A further object of the invention is to provide an air regulator for refrigerators, and a means whereby the actual interior temperature of a refrigerator may be observed from the exterior, and arranging the means to be unaffected by the temperature of the outside atmosphere.

With these and other objects of the invention in view reference is now had to the accompanying drawings in which—

Fig. 1 is a side elevation of a refrigerator car, with one of its sides removed to disclose the interior;

Fig. 2 is a side elevation of a refrigerator of smaller capacity, and having one of its sides removed;

Fig. 3 is a sectional elevation of the air regulator;

Fig. 4 is a plan view of the case;

Fig. 5 is a front elevation of the case showing the relative position of the parts;

Fig. 6 is an enlarged side elevation of a yielding contact point;

Fig. 7 is a plan view of the insulated hood;

Fig. 8 is a sectional view of a fragment of the hood showing the relative positions of the window and the thermometer; and

Fig. 9 shows the wiring diagram.

Having reference to the drawings like numerals refer to like parts throughout the several views and the numeral 1 refers to a refrigerator car having the usual side walls 2, a ceiling 3, the latter being also classed as a side wall, ice storage tanks 4 having a drip pan 5 that is provided with an outlet 6, a bulkhead 7, a screen wire guard 8, deflector

plates 9 mounted in the walls of the bulkheads, and cross pieces 10, with an inlet 11 sealed in the usual manner with a wedge shaped cover 12 (shown dotted in Fig. 1).

The loading space of the car is confined between the two bulkheads 7 and the course of the air currents is represented by the ar-

rows, these showing that the circulation of air is downward through the ice storage tanks and upward through a portion only of the loading space, and leaving space 13 in the upper center of the refrigerator without circulation which will be termed the warmer air zone.

The warmer air zone now constitutes that portion of the space in a refrigerator where there is little or no circulation of air, and where no circulation occurs it is obvious that the temperature will be higher than surrounding air circulating over ice.

When a refrigerator is first iced, and with the temperature of a refrigerator or its contents relatively high, the circulation will be more rapid due to the greater difference of the density of the air.

This is true whether in a refrigerator car, or other refrigerator (see Fig. 2), and hence to facilitate circulation in this zone and thus create a uniform temperature throughout the car, and in a manner that the outside temperature will have no effect on its operation an air regulating device 15 is devised that consists of a case 16 provided with a flange 17 wherewith to secure the case to the side wall 3 of the refrigerator and in the warmer air zone, and having a closure 18 that may be secured in the closed position to prevent molestation, securement being obtained by a lock and key (not shown), or by inserting a padlock through orifices 19 formed in the complementary lips 20 of the case and closure.

The case is preferably rounded at one end, as at 21, to conform to the shape of other parts of the device and carries a discharge duct 22 positioned concentrically with the rounded end above mentioned, and is extended through the wall of the refrigerator to form a means of communication between the warmer air zone of the refrigerator and the outside atmosphere.

The duct is preferably tubular in section and is provided with a damper 23 arranged to freely operate therein to close the duct tightly under certain conditions to be explained.

Mounted within the case is an operating mechanism 24 for operating the damper and this mechanism consists of a frame 25 enclosing the usual clockworks movement, which may be wound by a crank 26 that may be removed when not in use, with an indicator 27 attached to the frame to denote

whether the spring of the movement is wound, and including a tripping wheel 28 portrayed diagrammatically in Fig. 9.

A shaft 29 projects from one side of the frame and carries a crank 30, and a connecting rod 31 connects this crank with a complementary crank 32 attached to the damper 23 for operating that member.

As the operating mechanism is old in the art further description is deemed unnecessary.

Attached, preferably to the operating mechanism, is a thermostat 33 comprising the usual temperature controlled coil 34 attached to a post 35, and having a depending arm 36 positioned with its free end movable between two points 37 and 38, the latter points being attached to a movable plate 39 pivotally attached to the case 40 of the thermostat, at the point 41, by which latter means the points may be movable with respect to the arm. By this movement and with a pointer 42 arranged to move with the plate, and operating in conjunction with a gauge 43, the temperature at which the arm will contact either of the points 37 or 38 may be readily observed.

The post 35 and the two points 37 and 38 are provided with binding posts (not shown) and electric wires connect these binding posts with other parts in and for the following manner and purpose:

The above mentioned tripping wheel 28 forms part of the clockworks of the operating mechanism and consists of a wheel rotatable with a shaft 44 that is rotated by said clockworks. The wheel is provided with diametrically opposite projections 45 and positioned for engagement with these projections is a pivotally mounted dog 46 that is normally maintained in the path of the projections by a spring 47.

Attached to the dog is an armature 48, and in magnetic communication therewith is an electromagnet 49 coupled in a circuit from the batteries 50 to the wheel 28.

The wheel 28 also carries a spring contact point 51 and positioned on either side of the wheel are other contact points 52 and 53 with which the spring contact point 51 forms a contact as this point revolves with the wheel.

In operation the pointer 42 is set at a predetermined point on the gauge 43 which moves the two points 37 and 38 to a position to be contacted by the arm 36 at the temperature desired, as above mentioned, when a circuit is completed from the batteries 50 to the post 35, down the arm 36 to the point 38, to the contact point 53, through the spring contact point 51 and wheel 28 to the electromagnet 49, then back to the batteries completing the circuit.

The diagram in Fig. 9 shows this circuit just before the instant of completion, or

before the dog 46 has been drawn to the magnet, and with the completion of the circuit the wheel will be released by the magnet when it will start rotating under the influence of the operating mechanism.

The spring contact point 51 now breaks contact with the point 53 thus breaking the circuit and releasing the armature. The spring now restores the dog to its initial position in the path of the next succeeding projection, the wheel stopping as the projection is intercepted by the dog with the spring contact point contacting the contact point 52.

The operating mechanism is now set for further operation that will not take place however until the change of temperature has moved the arm over to the other point 37 when the dog will again be withdrawn and the wheel again permitted to rotate.

It is now obvious that the wheel is rotated one half a revolution and by properly adjusting the cranks 30 and 32 and the connecting rod 31 the damper will be opened with one half a revolution of the wheel and closed with the succeeding half rotation.

The thermostat is positioned adjacent to the duct and the bottom 54 of the case is provided with perforations 55 to enable the air of the warmer air zone to enter and thereby affect the thermostat by the actual temperature of the zone.

The gauge 43 is brought adjacent to the closure 18 for convenience of operation and visibility and is so positioned to be accessible when the closure is opened.

To simplify the renewal of the batteries and to compel a proper connection of the batteries in the circuit to be made yielding contact points 56 are provided that consists of an elongated tongue 57 hinged to the frame of the operating mechanism by means of uprights 58, the hinge portion of the tongue forming a shoulder 59 that will bear against the spring 60, the shoulder and spring being arranged to exert a pressure of the tongue against the binding posts 61 of the batteries and also to maintain the tongue in an upright position when changing batteries.

The tongues are also equipped with depending pieces 62 which rest on either side of the binding posts, while the yielding contact points are spaced apart to require proper positioning of the batteries before contact can be made, when the depending pieces will prevent the batteries from rotating out of contact.

Another object of this means of contact is to insure that contact is made properly before the closure is closed, for, with the tongues raised, they will project outward in a manner to prevent the closure from properly closing until they are properly seated on the binding posts.

5 Positioned on the exterior of the refrigerator and extended to connect with the case 16 is an insulated hood 63 consisting of a hood shaped device having a flange 64 where-
6 by it may be secured to the refrigerator, and
7 having its inner extending portion 65 projected to register with the rounded end 21 of
8 the case. By this arrangement the air of
9 the warmer air zone will enter through the
10 above mentioned perforations and will there-
11 by communicate the identical temperature
12 of the warmer air to the interior of the hood.

13 The hood is insulated by the use of double
14 walls, although other means of insulation
15 may be used, and is for the purpose of pre-
16 venting the temperature of the outside at-
17 mosphere from affecting the interior temper-
18 ature of the hood.

19 How to observe and note the interior tem-
20 perature of the warmer air zone from the
21 exterior a window 67 is placed in the hood,
22 and attached to the inside of the hood ad-
23 jacent to the windows is a thermometer 68.

24 The window may consist of glass suitably
25 secured in the wall of the hood, and the hood
26 is slanted at the point of the window to pro-
27 vide for ready visibility of the thermometer
28 that is secured to the hood by means of
29 clips 69.

30 For convenience in assembling an orifice
31 70 is provided in the top of the hood to re-
32 ceive the upper end of the duct, and this
33 with the upturned edge 71 of the bottom of
34 the case will properly secure the duct in the
35 assembly.

36 A brace 72 may be added if deemed neces-
37 sary to prevent the duct rotating with the
38 movement of the damper by the operating
39 means.

40 The hood when used on refrigerator cars
41 will preferably be positioned to one side of
42 the running board 73, as shown in Fig. 7,
43 so that the thermometer may be observed
44 therefrom.

45 In use the regulator is installed in the up-
46 per central portion of the refrigerator and
47 the thermostat is set to operate at the desired
48 temperature.

49 The refrigerator is now loaded, the doors
50 sealed against the outside temperature, and
51 the ice storage spaces filled with ice.

52 Now assuming that the thermostat is set
53 at 35 degrees, the ice absorbs the heat of the
54 refrigerator, a circulation being created by
55 the difference in density of the air in the
56 different parts of the refrigerator.

57 As above noted the circulation occurs short
58 of the warmer air zone, and with the tem-
59 perature of the air above the 35 degrees the
60 thermostat will cause the release of the op-
61 erating mechanism that will then open the
62 damper when the air will move through
63 the duct and thus start a circulation in the
64 zone.

65 The circulated air will now become mixed

with the cooler air of the refrigerator and
thus will have its temperature lowered un-
til when it reaches the 35 degree mark the
damper will close and thus retain the now
70 cooled air providing a uniform temperature
throughout the refrigerator.

71 With the damper open the air will move
72 into or out of the duct, depending upon the
73 relative density of the outside and inside
74 air, and this movement will be superinduced
75 by any movement of the air on the outside,
76 caused by a breeze or otherwise, a very slight
77 movement having the desired effect on re-
78 frigerators of small capacity, while in the
79 refrigerator cars the movement of the car
80 will create the necessary breeze with its at-
81 tendant movement of the air.

82 Where a refrigerator is sealed, as in a re-
83 frigerator car in transit, its interior temper-
84 ature may now be noted without breaking its
85 seal, the actual temperature may be obtained,
86 and by this means frequent and expensive
87 reicing will become unnecessary, while the
88 temperature will be maintained more near-
89 ally normal and uniform throughout the whole
90 car, normal being construed as being the
91 temperature at which the thermostat is set.

92 The outlets 6 of the drip pipes are made
93 use of to destroy any tendency to a partial
94 vacuum that might be created through the
95 duct, and which might interfere with the
96 movement of the air through the duct.

97 Having thus described my invention, I
98 claim—

99 1. In an air regulator for refrigerators, a
100 case positioned in the warmer air zone of
101 said refrigerator and provided with a
102 closure, a discharge duct positioned within
103 said case and extended to provide communi-
104 cation between the warmer air zone of the
105 refrigerator and the outside atmosphere, and
106 provided with a damper, an operating
107 mechanism mounted in said case in operable
108 connection with said damper, a thermostat
109 control positioned adjacent to said duct and
110 electrically connected to said operating
111 mechanism, contact points attached to said
112 operating mechanism to provide proper elec-
113 trical connections, and an insulated hood
114 mounted on said refrigerator and projected
115 inward to register with said case.

116 2. In an air regulator for refrigerators, a
117 case positioned in the warmer air zone of the
118 refrigerator and provided with a closure, a
119 discharge duct positioned within said case
120 and extended to provide communication be-
121 tween said warmer air zone and the outside
122 atmosphere, and provided with a damper, an
123 operating mechanism mounted in said case in
124 operable connection with said damper, a ther-
125 mostat control positioned in said case adja-
126 cent to said duct and electrically con-
127 nected to said operating mechanism, yielding
128 contact points attached to said operating
129 mechanism to provide proper electrical con-

nection of batteries in the electric circuit of said thermostat, and an insulated hood mounted on said refrigerator and projected inward to register with said case.

3. In an air regulator for refrigerators, a case positioned in the interior of the refrigerator, means to permit the air of said refrigerator to enter said case, a discharge duct extended through said case to provide communication between the air of said refrigerator and the outside atmosphere,

means to close said duct, means to thermostatically control said closing means, the thermostat of said control being mounted in the case in a position to be effected by the temperature of the air entering said case, an insulating hood mounted on the outside of said refrigerator in a manner to insulate the device from the outside temperature and to contain air that has entered said case. 15 20

In testimony whereof I affix my signature.
ELLOF S. RYERSON.
